DESIGN FOR A SMOKING PIPE

Karol Galashek, Seattle, Wash.

Application October 13, 1947, Serial No. 141,894

Term of patent 7 years

(Cl. D85—8)

To all whom it may concern:

Be it known that I, Karol Galashek, a citizen of the United States, residing at Seattle, in the county of King and State of Washington, have invented a new, original, and ornamental Design for a Smoking Pipe, of which the following is a specification, reference being had to the accompanying drawing, forming part thereof.

Fig. 1 is an elevational view of a smoking pipe embodying my new design.

Fig. 2 is a bottom plan view of the same.

Fig. 3 is a front end view of the pipe.

The dominant features of my design reside in the portions shown in full lines.

I claim:

The ornamental design for a smoking pipe, as shown and described.

KAROL GALASHEK.
